KNURLING MACHINE

Joseph J. Wittman, Detroit, Mich.

Application October 26, 1948, Serial No. 56,529

2 Claims. (Cl. 80—5.1)

1

The present invention relates to improvements in a knurling or expanding machine for knurling or expanding the inside and outside walls of an open end cylindrical object, such for example as a piston skirt or the like, and in particular to such a knurling machine which has automatic safety means for rendering the machine inoperative when excessive force is imposed on the knurling rollers by the objects being knurled.

The construction of the knurling machine of the present invention is particularly but not exclusively adapted to the knurling of the skirts on pistons for internal combustion engines, as more particularly set forth in the following specification.

Knurling of a piston skirt from the area below the lower ring groove to the end of the skirt expands the surface of the piston skirt and permits a tighter fit of the piston skirt in the cylinder. Knurling of the outer surface of a piston has been found to be very desirable, since the raised portions of the knurl provide the bearing surfaces required while the grooved portions provide oil grooves on the external surface of the piston and thus assure lubrication between the piston and the cylinder walls.

Piston knurling machines heretofore developed have been time-consuming in operation as they have utilized screw-threaded shafts and the like, for adjustably securing the pistons into knurling position under pressure. As distinguished from such prior devices, the knurling machine of the present invention provides a means by which a piston is locked in place under spring tension by one simple movement of the locking lever.

Conventional piston expanders or knurling machines are also limited as to the amount of piston skirt area which they can knurl on pistons having internal bosses or reinforcing ribs. Such bosses or reinforcing ribs present obstructions which either prevent passage of the knurling rollers used in conventional knurling machines or cause much breakage of the pistons if the knurling rollers are forced over such bosses or ribs.

It is, therefore, a principal object of the present invention to provide a knurling machine adapted to knurl piston skirts, which is so constructed that a piston skirt may be knurled from the lower ring groove to the bottom of said piston skirt, regardless of the internal construction of the said piston and in which provision is made to release the knurling pressure when required to eliminate breakage of the pistons.

It is a further object of the present invention

2

to provide a knurling machine which may be readily adapted to knurl piston skirts, in a very short time interval and in which loading and unloading of work in the machine is accomplished with a minimum of lost time.

It is another object of the present invention to provide a knurling machine adapted to knurl piston skirts, which includes an automatic safety device which renders the machine inoperative when an obstruction is encountered on said piston skirt or when the knurling rollers on said machine are subjected to an unduly heavy load.

It is another object of the present invention to provide a knurling machine adapted to knurl piston skirts, which can be rapidly adjusted to accommodate different sizes and types of pistons.

It is a further object of the present invention to provide a knurling machine adapted to knurl piston skirts, in which the piston is held in the machine under constant pressure during the knurling operation.

It is another object of the present invention to provide a knurling machine adapted to knurl piston skirts, which is provided with index markings so arranged that each successive section of a piston skirt to be knurled may be quickly indexed and located in the proper position for each operation of the machine.

Other objects of this invention will appear in the following description and appended claims, reference being had to the accompanying drawings forming a part of this specification wherein like reference characters designate corresponding parts in the several views.

In the drawings:

Fig. 1 is a top view of a knurling machine embodying the present invention.

Fig. 2 is a side elevation of the knurling machine shown in Fig. 1, with a piston shown in phantom.

Fig. 3 is a partial view of the top of the fixed anvil of the knurling machine shown in Fig. 1, and taken along the line 3—3 in the direction of the arrows, Fig. 1.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is

for the purpose of description and not of limitation.

The machine consists essentially of a fixed anvil 10 which is provided with a detachable rotatably mounted knurling roller 11. Complemental plates 12 are secured by the machine bolts 13 to the fixed anvil 10 and extend upwardly therefrom and in spaced relation to each other to provide a point for the pivotal attachment of the movable arm 14. The arm 14 is pivotally mounted as at 15 to the spaced plates 12 and extends outwardly and overhangs the end of the fixed anvil 10. A stop 16 is laterally disposed between the side plates 12 and is rigidly secured to the said side plates 12 by means of the bolt 17. The said stop 16 limits the upward travel of the movable arm 14. A shaft 18 is journaled in the movable member 14 and is provided with an operating crank 19 at one end and with a knurling roller 20 at its opposite end. The knurling roller 20 preferably is held in position on the shaft 18 by means of a set screw (not shown) so that said roller 20 may be rapidly removed and replaced. The knurling roller 20 moves vertically relative to the knurling roller 11 and is rotatably driven by the crank 19 through the shaft 18. Vertical pivoting movement of the arm 14 relative to the pivot point 15 is controlled through the locking lever 22 which is pivotally mounted as at 23 to the forward end of the arm 14. A link 24 is pivotally connected between the lever 22 and one leg of the bell crank 25 which is pivotally mounted as at 26 to the upper portion of the side members 12. The other leg of the bell crank lever 25 is connected with a clevis 27 to which is secured a screw-threaded adjusting bolt 28 which has an adjusting nut 29 mounted thereon. The nut 29 may be moved to vary the compression on the compression spring 30. The spring 30 is seated at one end on a washer 31 which is movable with the nut 29 and at the other end on a spring seat 32 which is pivotally connected as at 33 with the side portions 12 of the device. The adjusting bolt 28 extends through the spring seat 32 and adjusts the throw or amount of movement which the linkage permits in connection with the handle 22. This adjustment is independent of the adjustment of the nut 29 for varying the compression on the spring 30.

When the operating handle 22 is moved to the position for the knurling rollers to engage a piston designated as 34 in Fig. 2, the links 24 are so arranged that the parts are only slightly beyond center. This is controlled by adjustment of the adjusting screw 35 which contacts the bell crank 25 in the operating position. Thus, when the knurling roller 11 strikes a projection on the inside of the piston 34 as for example a boss, reinforcing rib or the like, an upwardly directed force is exerted on the knurled roller 20 and this will trip the linkage in such a way that the roller 20 is free of compression and hence breakage of the piston is eliminated.

During the operation of the device, the roller 20 is held against the outside of the piston by a spring tension force which is exerted by the spring 30. By varying the tension on the spring 30, the force constantly exerted on the roller 20 may be varied. This construction is adequate to accommodate the ordinary variations in the thickness of piston walls and the like.

Markings 36, Fig. 3, are provided on the upper surface of the extended portion of the fixed anvil 10. The bottom of the piston skirt is placed ad-

jacent the first of these markings and the piston 34 is locked into place by counterclockwise movement of the locking lever 22. The crank 19 is rotated, and a section of the piston skirt is knurled. Clockwise movement of the locking lever 22 releases the pressure on the piston 34, and the bottom of the piston skirt is moved to the second of said markings 36. This operation is repeated with the successive markings 10 until the knurling of the piston skirt is completed. The markings 33 are so spaced that the knurled sections will slightly overlap, and no part of the piston skirt will remain unknurled.

The fixed anvil 10 is tapered near the roller 11, 15 and the roller 11 is of small diameter so that internal obstructions within the piston will not prevent the desired knurling on the inside of the piston skirt.

The knurling machine shown in the drawings is 20 a vise model adapted to be gripped in a machinist's vise. The said machine may also be provided as a bench type by providing suitable flanges or fastening lugs to secure the entire unit to a work bench.

25 The rollers 11 and 20 as shown in the drawings have the same angular position of their respective teeth. Due to the fact that the said rollers are disposed 180 degrees apart, they rotate in opposite directions as the piston skirt is rolled between them. Thus, the knurled pattern inside the piston runs in a different direction than the knurled pattern outside the piston. This reinforces and stiffens the piston walls since the knurled ribs run in opposite and crossing directions.

30 35 The knurling rollers 11 and 20 may have a plain surface if the device is to be used as a piston expander and knurling is not desired. Any desired type of knurled pattern may be provided by changing rollers as required to provide the desired 40 knurled design.

Having thus described my invention, I claim:

1. In a knurling machine, the combination of 45 two complemental side plates; a fixed anvil disposed at the bottom of said side plates and extending forwardly therefrom; a roller rotatably and detachably secured adjacent the forward end of said fixed anvil; a movable arm pivotally attached to said side plates above said anvil and extending forwardly from said side plates; a shaft 50 journaled in said movable arm; a roller detachably attached to the said shaft at the forward end and above the first-mentioned roller, a crank affixed to the other end of said shaft; means for locking the cylindrical object between said rollers 55 and resiliently holding said object in place under adjustable spring tension, said means forming an adjustable safety device which will trip when a predetermined load is exceeded on said rollers and including a locking lever pivotally secured to 60 the forward portion of said movable arm, links pivotally connected at one end to said locking lever and at the other end to one leg of a bell crank which is pivotally attached to said side plates, a clevis pivotally attached to the other leg 65 of said bell crank, a bolt screw-threaded to said clevis at one end and extending through a pivotal spring seat at the other end, a nut screwed onto said bolt between said clevis and said spring seat, a spring interposed between said nut and said 70 spring seat, and surrounding said bolt, and an adjusting screw extending through said locking lever and abutting said bell crank when the locking lever is in the operative position, said adjusting screw determining the position of the locking 75 lever in the operative position.

2. In a knurling or expanding machine adapted for knurling or expanding the inside and outside walls of a cylindrical object such as a piston skirt and which will accommodate differences in wall thicknesses of said object, the combination of two complementary side plates; a fixed anvil disposed at the bottom of said side plates and extending forwardly therefrom; a roller rotatably and detachably secured adjacent the forward end of said fixed anvil; a movable arm pivotally attached to said side plates above said anvil and extending forwardly from said side plates; a shaft journaled in said movable arm; a roller detachably attached to the said shaft at the forward end and above the first-mentioned roller, a crank affixed to the other end of said shaft; and means for locking the cylindrical object between said rollers and resiliently holding said object in place under adjustable spring tension, said last-named means comprising a locking lever pivotally secured to the forward portion of said movable arm, links pivotally connected at one end to said locking

5
10

lever and at the other end to one leg of a bell crank which is pivotally attached to said side plates, a clevis pivotally attached to the other leg of said bell crank, a bolt screw-threaded to said clevis at one end and extending through a pivotal spring seat at the other end, a nut screwed onto said bolt between said clevis and said spring seat, and a spring interposed between said nut and said spring seat and surrounding said bolt.
